(57) **CLAIM**

The ornamental design for “piston pump,” as shown and described.

DESCRIPTION

FIG. 1 is a front view of a first embodiment;

FIG. 2 is a rear view of the first embodiment;

FIG. 3 is a view from the lower end of FIG. 1;

FIG. 4 is a view from the upper end of FIG. 1;

FIG. 5 is a view from the right end of FIG. 1;

FIG. 6 is a view from the left end of FIG. 1; and,

FIG. 7 is a perspective view of the embodiment.

The broken lines are included for the purpose of illustrating elements of the piston pump that form no part of the claimed design.
